TRANSMITTER OUTPUT COUPLING CIRCUIT

Oliver I. Steigerwalt, Niagara Falls, N. Y., assignor to the United States of America as represented by the Secretary of War

Application February 18, 1946, Serial No. 648,543

3 Claims. (Cl. 250—36)

1

This invention relates in general to electrical apparatus and more particularly to magnetron oscillators.

In the generation of ultra high frequency oscillations it is often convenient to use a magnetron oscillator to produce high frequency waves at relatively high power levels. Various types of magnetron tubes are in use at the present time, one of them being the split-anode transit-time type. In contrast to certain other varieties of magnetrons in common use the split-anode type requires an external plate tank circuit. At frequencies in the U.-H.-F. bands such a tank takes the form of a resonant parallel line. The line is tuned by moving some form of shorting means associated therewith in order to change the effective length of the wires forming the line. The general operation of a split-anode magnetron is clearly set forth in chapter 10 of "Ultra High Frequency Techniques," by J. G. Brainerd et al., D. Van Nostrand, Inc., New York, 1942, and will not be elaborated here.

Coupling from the tuned line to an output means is customarily done by inserting a probe into the field between the wires or by connecting a conductor directly to one of the wires. Since the coupling arrangement must lie between the magnetron and the shorting bar, it is clear that if the shorting bar is to be moved over any considerable range of positions, the coupling means will have to be repositioned to avoid interference with the motion of the shorting bar. In addition, if the degree of coupling is to be changed the coupling means must be adjusted independently of the shorting bar. If it is desired to re-tune the magnetron to a new frequency and retain the same degree of coupling, both shorting bar and coupling means must be moved.

Accordingly it is one of the objects of my invention to provide a means for coupling to the tank circuit of a split-anode magnetron oscillator.

Another object is to provide proper coupling for maximum oscillator efficiency over a relatively wide range of frequencies.

Still another object is to provide means for minimizing coupling adjustments with tuning changes.

Still another object is to provide a simple tuning arrangement for a magnetron oscillator such as described hereinafter in this specification.

Briefly, my invention contemplates the use, for coupling, of a short section of coaxial line, the center conductor of which makes contact with one wire of the tank circuit of a split-anode type

2

of magnetron oscillator. The outer conductor of the line is not connected to the resonant circuit and gives an effect equivalent to that of an inductance in series with the output line. By means of this inductive effect the spacing between a shorting bar associated with the tank circuit and the coupling point may be maintained constant as the shorting bar is moved to effect a change in frequency, while the degree of coupling remains unchanged. Means are provided for driving the shorting bar and simultaneously moving the member coupling to the tank circuit line. Means also are provided for moving the latter member independently of the aforesaid driving means.

15 The principles and operation of my invention will be more apparent to those skilled in the art upon reference to the following specification, claims, and to the drawings in which:

Fig. 1 is a perspective view of one embodiment 20 of my invention;

Fig. 2 shows an enlarged view of a portion of the apparatus of Fig. 1;

Fig. 3 is a view of a portion of the mechanical drive for the moving members; and,

25 Fig. 4 is a schematic diagram of the essential elements of the apparatus in Fig. 1.

Reference is now made to Fig. 1 in which the relations of the various members of one embodiment of my invention with one another are shown 30 in perspective. A split-anode magnetron tube 5 has connected to it two rod-like conducting members 6 and 7 forming the tank circuit for the tube. The magnetron envelope is supported by a rest 9 which is mounted in a box 10 a portion 35 of which is broken away to show its contents. The interior surfaces of box 10 are covered with a conducting material so that the box forms an electrostatic and an electromagnetic shield for the electrical elements therein. Magnetic pole pieces 11 are mounted on either side of the magnetron tube 5 in well known fashion to provide the requisite magnetic flux.

40 A metallic plate 14 edged with spring fingers 15 is pierced to allow it to be slipped over rods 6 and 7 and yet maintain a sliding contact with the rods. Plate 14 provides a short circuit between rods 6 and 7 and comprises what has been referred to in general as a shorting bar. Fingers 45 15 make contact with the conducting lining of box 10 thus tending to hold plate 14 in position and providing an electrical path between the plate and the box.

The output coaxial coupler is positioned between plate 14 and magnetron 5, center conduc- 55 tor 18 terminating in a spring attachment 19

which makes sliding contact with rod 6. The coupler has a collar 20 furnished with spring fingers 21 which is slipped over outer conductor 22. The coaxial line passes through a slot 29 in the rear wall of box 10 and makes connection with output line 26 in such a fashion as to transfer power thereto regardless of the position of contacts 19 along the length of rod or wire 6. Outer conductor 22 is electrically connected to the conducting lining of box 10 through collar 20 and springs 21.

A threaded shaft 25 may be seen through slot 29 and in practice has been positioned outside of box 10. This shaft engages with a carriage to which plate 14 is mechanically connected in order that the operation of some external control such as handwheel 30 will cause the movement of plate 14 along the axis of box 10. Blocks 32 and 33 which slide on guide rod 34 form a portion of the support and guiding means for this carriage. There has been omitted from this view of my apparatus, for purposes of ease of illustration and clarity, a second shaft and handwheel mechanism which serves to alter the spacing between the output coupler and the shorting plate, and which will be shown in Fig. 3.

Further details of the shorting plate and coupling apparatus are shown in Figs. 2 and 3. Fig. 2 is a top view showing the manner in which the movable members comprising the coupling means and the shorting means inside box 10 are brought through the aforementioned slot in the wall of the box. A member 36 attached to shorting plate 14 passes through the slot and is rigidly fastened to shorting plate carriage 37. Outer conductor 22 of the coaxial output line is connected to coupling block 38 and the members 37 and 38 are shown more clearly in the showing of Fig. 3. The member 38 is constructed to form a link between the coaxial line connected to the tank circuit and transmission line 26 which carries power to an antenna or other load. Blocks 32 and 33 and guide rod 34 cooperate to support and guide the shorting plate carriage and the coupling block.

Fig. 3 shows in some detail one method of driving shorting plate carriage 37 and coupling block 38. Threaded rod 25 passes through both of these members but only the hole in carriage 37 is threaded to engage with the threads on the rod, the hole in block 38 being bored large enough to allow free passage of the rod therethrough. Rod 40 is not shown in Fig. 1 but is parallel to and substantially the same length as rod 25, terminating in a handwheel or crank mechanism similar to that attached to rod 25. Rod 40 is unthreaded and a groove or keyway 41 runs the length of it. Sleeve 42, the exterior of which is threaded, fits over rod 40 and key 43 joins the sleeve to the rod so that the former is free to move along the latter but rotation of the rod is followed by the sleeve. Sleeve 42 is loosely attached to shorting plate carriage 37 by means of collar 45 which fits into a similarly shaped groove or slot in the carriage. Therefore the sleeve can rotate freely with shaft 40 but is constrained to move longitudinally with the carriage. An additional guide rod 47 is provided to support and direct carriage 37.

An inspection of Fig. 3 will show that revolution of rod 25 will produce equal increments of longitudinal displacement in both carriage 37 and coupling block 38, while rotation of shaft 40 will produce longitudinal motion only in cou-

pling block 38, thus achieving the desired motion of the shorting plate and output coupling line.

Referring to Fig. 4, there is shown a schematic equivalent diagram of a split-anode magnetron, a resonant line tank, and a coaxial output means for explanatory purposes. In this figure dimension A represents the distance between shorting means 50 and magnetron anode 51, while dimension B is the distance between shorting bar 50 and the output coupler attachment 52. Coil 53 represents the inductance offered by that section of the outer conductor of the coaxial line 54 which projects into the box enclosing the oscillator. This inductive effect is due to currents flowing over the outer surface of the outer conductor in the region inside the box or enclosure. The amount of inductive effect can be adjusted by changing the shape of the portion of the output line outer conductor extending into the cavity of the box.

Hence it is possible to adjust dimensions A and B independently to a given value of frequency and optimum degree of coupling and then to alter both dimensions by equal increments while retaining optimum coupling at any frequency. In this way a single control may be used to make adjustments after the original settings combining convenience and speed of adjustment with maximum oscillator efficiency at all times.

While there has been described hereinabove what is at present considered to be a preferred embodiment of the present invention, it will be obvious to those skilled in the art that changes and modifications may be made therein without exercise of inventive ingenuity. Hence, I claim all such modifications and adaptations as may fall fairly within the spirit and scope of the hereinafter appended claims.

What I claim is:

1. In an ultra high frequency oscillator a split-anode magnetron tube, a section of parallel-wire transmission line, means connecting said line section to the anode electrode of said magnetron tube, a box-like structure of conducting material enclosing said magnetron tube and said section of transmission line, a plate of conducting material positioned transversely to the longitudinal axis of said line section and making electrical contact with said line and said box-like structure, a coaxial output line positioned between said magnetron tube and said plate, the center conductor of said coaxial line making contact with one of the conductors of said parallel-wire line and the outer conductor of said coaxial line projecting into said box-like structure and making electrical contact only with said box-like structure, means for varying the spacing between said conducting plate and said magnetron tube, and means for simultaneously varying the spacing between said conducting plate and the point of contact of said coaxial output line with said parallel-wire line.

2. In an ultra high frequency oscillator an electron discharge device, a tuned parallel-wire tank circuit, means for electrically connecting said electron discharge device and said tank circuit, electrical shielding means substantially enclosing said tank circuit, and output coupling means comprising a coaxial transmission line, the inner conductor of which makes electrical contact with one of the conductors of said tank circuit and the outer conductor of which makes electrical contact with said shielding at its point of passage through said shielding, and projects

a predetermined distance into the enclosure formed by said shielding, a movable conductive wall in said shielding means connected to the conductors of said tank circuit for short-circuiting said conductors, means for moving said wall and said output coupling means in unison along the conductors of said tank circuit.

3. The apparatus defined in claim 2 further including means for altering the spacing between said short-circuiting wall and said output coupling means.

OLIVER I. STEIGERWALT.
